UNITED STATES PATENT OFFICE.

BETSEY C. HAUPT, OF NEW YORK, N. Y.

DESIGN FOR A CHILD'S CARRIAGE OR SIMILAR ARTICLE.

Application filed April 26, 1929. Serial No. 31,012. Term of patent 7 years.

To all whom it may concern:

Be it known that I, BETSEY C. HAUPT, a citizen of the United States of America, residing at New York, in the county of New York and State of New York, have invented a new, original, and ornamental Design for Child's Carriage or Similar Article, of which the following is a specification, reference being had to the accompanying drawing, forming a part thereof.

The figure is a perspective view of a child's carriage showing my new design.

I claim:—

The ornamental design for a child's carriage or similar article as shown.

BETSEY C. HAUPT.
